UNITED STATES PATENT OFFICE.

JOSEPH S. MITCHELL, OF CHICAGO, ILLINOIS, ASSIGNOR TO SULLIVAN MACHINERY COMPANY, A CORPORATION OF MASSACHUSETTS.

CORE DRILL.

Application filed November 5, 1923. Serial No. 672,796.

My invention relates to core drills.

It has for its object to provide an improved core barrel and more particularly an improved core barrel of the type adapted to 5 oil or gas well drilling and wherein as a result of the large and heavy cores dealt with and the use of mud fluid, a barrel of increased strength and adapted to provide passage means of adequate size, is required.

10 More particularly my invention has for its objects to provide an improved core lifter shell adapted to use in such a barrel.

In the accompanying drawings I have shown for purposes of illustration one form 15 and a modification thereof which my invention may assume in practice.

In these drawings,—

Fig. 1 is a partial vertical section showing my invention embodied in a barrel.

20 Fig. 2 is a transverse section on line 2—2 of Fig. 1.

Fig. 3 is a transverse section on line 3—3 of Fig. 1.

25 Fig. 4 is a transverse section on line 4—4 of Fig. 1.

Fig. 5 is a fragmentary view similar to Fig. 4, illustrating a slightly modified form of construction.

In this illustrative construction I have 30 shown a barrel of the general construction described and claimed in my copending application Ser. No. 579,038, filed Aug. 1, 1922, comprising an internally and externally fluted bit 1 and a similar guide 2 above the 35 bit, these elements being connected by a core lifter shell 3 of improved construction, hereinafter described and carrying therein a usual core lifter 4, and all being adapted to deliver mud fluid to the bottom of the hole.

40 Referring more particularly to my improved construction it will be noted that the shell 3 is threaded to external threads on reduced opposite ends of the members 1 and 2, by internal threads on and extending 45 a substantial distance inward from the opposite ends of the member 3. Further, the outside diameter of the intermediate portion of the shell is uniform and slightly less than the outside diameter of both the bit and the 50 guide, though slightly greater than circles substantially including the bottoms of the flutes in those members, while reduced portions 5 and 6 at opposite ends of the member 3 are provided, respectively adjacent the 55 inlet ends of the flutes in the guide 2 and the

outlet ends of the external flutes on the bit 1. More particularly, it will be noted that the area between the intermediate portion and the walls of the hole is substantially the same as the sum of the areas of the flutes 60 in the bit or guide. Moreover, the reduced portion 5 is of a slightly larger outside diameter than a circle substantially including the bottoms of the grooves in the member 2 and is connected to the intermediate portion 65 of the member 3 by a sloping, and preferably conical, portion 7. It will further be noted that the same general construction has been used in connection with the reduced portion 6 which is of substantially the same outside 70 diameter as a like circle substantially including the bottoms of the external grooves in the bit 1 and is connected to the intermediate portion of the member 3 by a sloping or conical portion 8. As shown in Fig. 75 5 the core lifter shell 3 may be externally fluted, as at 9, throughout the length of the intermediate externally enlarged portion to provide a slight additional flow of fluid to pass the shell without substantially weakening the shell.

As a result of my improved construction, it will be observed that since it is made possible to increase the amount of metal in the intermediate portion of the member 3 and 85 to thread into that portion, the strength of that member is materially increased. It will further be observed that, by reason of the proper proportioning of this member 3 with its intermediate outside diameter providing a flow area adapted to cooperate with the flow areas in the bit and guide, and by reason of the reduced portions at the ends of this intermediate portion, the desired 90 fluid flow between the bit and the guide is 95 maintained. Further, as a result of this construction, it will be noted that it is possible to obtain the desired strength and fluid flow without any necessity for fluting this particular member and thereby necessarily weakening the same, although obviously should a slight additional flow be desired, the construction of the member 3 will permit of a certain amount of fluting, as indicated in Fig. 5, without substantial weakening.

While I have in this application specifically described one form and a modification thereof which my invention may assume in practice, it will be understood that 110

this form and modification of the same are shown for purposes of illustration and that the invention may be modified and embodied in various other forms without departing 5 from its spirit or the scope of the appended claims.

What I claim as new and desire to secure by Letters Patent is:

1. In a core barrel comprising guide and 10 bit portions, a core lifter shell connecting the same and having an intermediate portion of greater external diameter than its ends, said intermediate portion being of smaller external diameter than said guide 15 and bit portions.
2. In a core barrel comprising bit and guide portions having external fluid passages therein, a core lifter shell connecting the same and having an intermediate portion of greater external diameter than its 20 ends, said intermediate portion being of smaller external diameter than said bit and guide portions and so proportioned as to permit a free flow of fluid between said bit 25 and guide portions.
3. In a core barrel comprising externally grooved bit and guide portions, a core lifter shell connecting the same and having an intermediate portion of greater external 30 diameter than the portions of the same adjacent the bottoms of the grooves in said bit and guide portions, said intermediate portion being of smaller external diameter than said bit and guide portions.
35. 4. In a core barrel comprising externally grooved bit and guide portions, a core lifter shell connecting the same and having an intermediate portion of greater external diameter than the portions of the same adjacent 40 the bottoms of the grooves in said members, said smaller portions each being of substantially the diameter of the bottoms of the grooves in its adjacent member.
45. 5. In a core barrel comprising externally grooved bit and guide portions, a core lifter

shell connecting the same and having an intermediate portion of greater external diameter than the portions of the same adjacent the bottoms of the grooves in said members, said last mentioned portions each being of 50 substantially the diameter of the bottoms of the grooves in its adjacent member and the body portion of said shell being of smaller external diameter than the bit.

6. A core barrel comprising an externally 55 fluted bit, an externally fluted guide, and an unfluted intermediate core lifter shell of greater external diameter intermediate its ends threaded thereto by threaded portions extending into said intermediate portion and forming a unit of substantially uniform strength throughout its length and forming throughout its length an external passage of an area substantially equal to the fluid flow area along said bit and guide. 60

7. In a core barrel comprising externally 65 grooved bit and guide portions, a core lifter shell connecting the same and having an intermediate portion of greater external diameter than the portions of the same adjacent 70 the bottom of the grooves in said members and so proportioned as to present a flow area substantially the same as the area of the groove in said grooved portions, said smaller portions each being of substantially 75 the diameter of the bottom of the grooves in its adjacent member.

8. In a core barrel comprising externally 80 grooved bit and guide portions, a core lifter shell threaded thereto by threaded portions extending into said shell, said shell having an intermediate portion of greater external diameter than the portions of the same adjacent 85 the bottoms of the grooves in said bit and guide portions, said smaller portions each being of substantially the diameter of the bottoms of the grooves in its adjacent member.

In testimony whereof I affix my signature.

JOSEPH S. MITCHELL.
